POSTER FRAME

David S. Howell, Troy, Mich., assignor to Arlington Aluminum Company, Detroit, Mich., a corporation of Michigan

Filed Dec. 9, 1965, Ser. No. 129

Term of patent 14 years

(Cl. D1—12)

FIG. 1

4

FIG. 2

FIG. 3

I claim:

The ornamental design for a poster frame, as shown.
